CLAIM

The ornamental design for a shoe support, substantially as shown and described herein.

DESCRIPTION

FIG. 1 is a front perspective view of a shoe support showing our new design;

FIG. 2 is a top plan view thereof with portions of the rear strap shown broken away and unbuckled;

FIG. 3 is a side elevational view thereof with portions of the strap omitted for ease of illustration;

FIG. 4 is a rear elevational view thereof;

FIG. 5 is a front elevational view thereof.

FIG. 1

FIG. 2

FIG. 3

FIG. 5

FIG. 4
